BOAT HULL CONSTRUCTION AND
PROPELLIONWilliam S. Brian and Ferdinand J. Birk,
Owensboro, Ky.

Application April 12, 1943, Serial No. 482,792

8 Claims. (Cl. 115—11)

This invention relates to boat hull construction and propulsion particularly designed to obtain high speed with maximum conservation of power.

One of the objects of this invention is to provide a boat or ship of that type, the under side of which is formed as a longitudinal tunnel by the provision of lateral downwardly extending longitudinal fins, with which propulsion is secured by means of a blower on the ship which discharges air beneath the hull under sufficient pressure to lift the hull and support it upon a layer of compressed air confined between the fins, and of sufficient velocity to propel the boat forwardly by reaction of the escaping air flow against the water wake.

In a boat of this type, as previously known, an example of which is disclosed in the patent to Dunajeff, No. 1,412,848, granted April 18, 1922, the bow portion of the boat is designed to travel normally supported by the water, creating a resistance to forward movement which practically nullifies the forward propulsive force.

One of the objects of the invention therefore is to provide the hull with a downwardly and rearwardly extending injector or venturi at the front, formed by a swinging vane anterior to the bow proper and forming with it a Venturi orifice which changes its pitch with the volume of air supplied by the blower, increase in the volume of air causing said Venturi vane to be pulled away from the water and toward the bow proper, causing air to be sucked into the tunnel or tunnels at the front of the boat by the partial vacuum created in said venturi, so that the water displacement of the boat is reduced solely to the volume of the submerged portions of the fins, whereby forward propulsion is provided not only by the impact of the escaping air on the wake, but also through the partial vacuum created in front of the Venturi vane as well as by the partial vacuum produced in front of the blower which furnishes the motive power.

A further object of the invention is to provide a boat hull of such design that it will, when supplied with air at sufficient pressure, ride with enough clearance between the hull and the water, yet sealed by the venturi in front and by lateral fins, so that when traveling at high speed in rough sea it will allow the waves to come in contact with the Venturi vane only, causing said vane to swing toward the hull, permitting the boat proper to ride over the waves without coming into direct contact with any great part of them.

Other objects of the invention will appear as

the following description of a preferred embodiment thereof proceeds.

In the drawings which accompany and form a part of the following specification, and throughout the several figures of which the same characters of reference have been employed to designate identical parts:

Figure 1 is a side elevation of a boat or ship, embodying the principles of the invention, the hull being shown in rest position;

Figure 2 is a similar view showing the position of the vessel and of the bow and stern vanes when in forward motion;

Figure 3 is a front view in elevation;

Figure 4 is a cross-sectional view illustrating the stabilizing function of the middle fin;

Figure 5 is a front end view, partly in section, showing a slightly modified form of the invention;

Figure 6 is a fragmentary side view in vertical section, of the modification shown in Figure 5;

Figure 7 is a view similar to Figure 5, showing the hull in listed position;

Figure 8 is a longitudinal vertical section of another modification of the invention;

Figure 9 is a front view in elevation, of still another form of the invention.

Referring now in detail to the invention as illustrated in Figures 1 to 4, inclusive, the numeral 1 represents as a whole the hull proper, having the bow 2, stern 3, bottom 4 and deck 5. The sides of the hull proper are produced forwardly, rearwardly and in a depth direction with respect to the hull proper, forming the longitudinal side fins 6 and 7 which are sufficiently deep so that their lower portions are submerged in all positions of elevation of the boat. A central fin 8 may be provided parallel to the side fins for effecting stabilization of the hull, although the central fin is not essential to the broad inventive concept.

A hood structure 9 is provided anterior to the bow 2, the forward portion of which, as shown, is supported by the bow as well as by the forwardly extending portions of the fins 6 and 7. The central portion of the hood 9 is constructed to form a blower housing 10, the front of which is preferably, but not necessarily, in a transverse plane perpendicular to water level and the posterior portion of which inclines downwardly toward the rear, communicating with the longitudinal tunnels 21 and 22 formed beneath the bottom 4 and between the downwardly extending fins 6, 7 and 8.

A power plant 11 is mounted in the boat having

a shaft 12 which extends into the housing 10 and operates a blower rotor 13, preferably of the wind-tunnel type, mounted in the housing 10. A swinging bow vane 14, made in two parts 14a and 14b to pass the middle fin 8, is pivotally mounted at the lower forward end of the hood structure 9, and is of such depth that the lower end 15 is submerged when the boat is at rest, even when it is lifted on a cushion of air just prior to assuming forward motion. The bow vane is normally inclined downwardly toward the rear but divergently to the bow 2, as shown in Figure 1, being limited in its amplitude of outward swing by the stops 16 formed on the fins 6, 7 and 8. The bow vane 14 is limited as to its inward swing by the stops 17, also formed as part of or secured to said fins. The depth of the bow vane is such that when it rests against the stop 17, the lower end 15 is above water level in the lifted position of the hull.

A stern vane 18 is pivotally mounted at the stern of the hull between the fins 6 and 7, being of sufficient depth to have its lower end 19 submerged when the boat is in its lifted position prior to its assuming forward motion. Said stern vane, as shown, is biased towards vertical position by a spring 20 of such strength as to resist the opening movement of said stern vane until the air pressure beneath the hull is greater than that merely sufficient to lift the hull, beyond which pressure the stern vane swings upwardly, permitting the escape of air. Other means, the equivalent of the spring 20 may be employed to control the stern vane.

The operation of the boat is as follows. Normally, when the blower 13 is not running, the vessel will rest at the normal water level represented by the line ab, the hull proper displacing sufficient water to support the hull. When the blower is started, a large volume of air under considerable pressure and velocity is forced beneath the boat within the confines established by the fins 6 and 7 and the bow and stern vanes 14 and 18, respectively. This lifts the hull above the water level to a position, with respect to said water level indicated by the line cd. In this position the bow vane 14, as well as the stern vane 18, still dip beneath the surface of the water while the side fins 6 and 7 are still submerged, so that no air escapes, and there is no forward movement. As the pressure and velocity of air delivered by the blower increases, the resistance of the spring 20 will be overcome so that the stern vane 18 swings upwardly toward the rear until the lower edge 19 emerges from the water, providing an exit at the stern for the escape of air. This rearwardly escaping air jet is confined between the rearwardly extending portions of the side fins 6 and 7 so as to secure maximum reactive propulsive pressure against the water wake rearwardly of the stern. As soon as a current of air has thus been established, the increased velocity of the jet from the blower has a practical Venturi effect in drawing the bow vane 14 inwardly against the stop 17, lifting the lower edge of said vane above the water level. The injector action of the air jet passing between the bow 2 and the bow vane 14 entrains a jet of air from the body of air in front of the ship, drawing this air through the space beneath the raised lower edge of the bow vane 14.

With the bow and stern vanes thus raised, an open ended air tunnel is formed beneath the hull and between the fins 6 and 7, the boat being entirely lifted from the water excepting as to the

submerged portions of the fins 6 and 7, so that the total displacement which has to be resisted is limited to the volume of the submerged portions of the fins 6 and 7. Resistance to forward propulsion is thus reduced to a minimum.

The propulsive force is not only the reaction of the rearwardly moving column of air against the water wake, but it is also augmented by the vacuum produced in front of the bow vane 14 and by the vacuum created in front of the blower where the latter faces in a forward direction, as shown. With the propulsive power thus increased, and the displacement resistance diminished to a minimum, a vessel constructed according to the principles of the subject invention should be capable of making great speed with comparatively small expenditure of power.

The purpose of the central fin 8 is to quickly stabilize the boat to dampen rolling of the hull. It is obvious from Figure 4 that if air is passing through the longitudinal tunnels 21 and 22 defined between the fins 6, 7 and 8, and the boat rolls to the position shown, the increased air pressure in the tunnel 21 and decreased pressure in the tunnel 22 will quickly restore the vessel to an even keel.

While the Venturi actuation of the front vane 14 is desirable as giving an added impetus to the forward movement of the hull through the entrainment of forward air with the resultant vacuum in front of the bow vane, this action is not essential, it being merely necessary that the bow vane be hinged and that it be of such length as to remain submerged longer than the stern vane. Then when the stern vane lifts, establishing an air jet against the water wake so that the hull begins to move forward, the bow vane swings back until its bottom edge just trails the water, preserving an air seal between said vane and the water, the forward resistance between the boat and the water being thus reduced to a minimum.

In that form of the invention shown in Figures 5 and 6, the chamber within the blower housing 10 is provided with a vane 23, journaled about that part of the shaft 12 which extends within the housing 10 and which is normally in the vertical plane of said middle fin when the hull is on an even keel, and is balanced by the weights 26 or other equivalent means so that it remains in a vertical plane regardless of the list of the hull. The middle fin 8 extends within the housing 10 substantially up to the lower edge of the vane 23. Thus, when the hull is in listed position, as illustrated in Figure 8, the vane 23 diverts the major proportion of the output of the blower 13 into the depressed tunnel, further increasing the air compression in said tunnel and the more quickly stabilizing the hull.

Figure 8 shows a modified form of the invention similar to that disclosed in Figures 1 to 4, excepting that the depth of draft created by the downwardly extending fins 6, 7 and 8 is relieved by having the lower portions of said fins constructed in the form of a series of lapping dagger-boards 27 pivoted to the fins at their forward ends, and which lift upon making contact with the bottom, permitting the vessel to navigate in shallow waters.

Figure 9 depicts a modified form of the invention which is, in general, similar in construction and mode of operation to that shown in the group of Figures 1 to 4, inclusive, but which differs from the latter in that independent blowers 75, 28 and 29 in individual housings 30 and hoods

31, independently serve the respective tunnels 21 and 22. The provision of the two blowers adds flexibility to the operation and control of the vessel, in that the speeds of the blowers may be independently varied to effect stabilization of the hull when rolling and that through independent control of the blower speeds differential action of the Venturi vanes 14a and 14b may be produced as well as different pressures at opposite sides of the water wake at the stern 10 whereby steering of the vessel through differential blower pressures may be accomplished.

It is, of course, to be understood that the illustrated embodiment of the invention is largely diagrammatic and serves solely to illustrate the broad inventive concept. The details of construction and the arrangement of parts, as shown, are therefore not to be construed as limiting the invention which is defined in the appended claims.

What we claim as our invention is:

1. In a power boat, the combination of a hull having longitudinal side fins extending depthwise below the hull bottom forming a longitudinal tunnel, a blower on said boat for delivering air to the forward part of said tunnel in a rearward direction, a stern vane at the rear of said tunnel having means imparting a biasing force thereto in a direction to close said tunnel, a hinged bow vane normally closing the front end 30 of said tunnel whereby said boat is lifted on a layer of air under pressure accumulated in said tunnel, said stern vane being opened by air pressure in said tunnel in excess of said biasing force to discharge the air flow from said tunnel against the water wake, and an injector at the forward end of said tunnel through which said blower delivers air to said tunnel, effective when the boat moves forward responsive to the reactive force of air against the water wake, to lift said bow vane above the water, entraining air from beneath said bow vane, thereby creating a forward vacuum which adds impetus to the forward movement of the boat.

2. Power boat as claimed in claim 1, the induction end of said blower facing forwardly whereby the vacuum created in front of said blower is an added component of the forward propulsive force.

3. Power boat as claimed in claim 1, including a central longitudinal fin extending depthwise beneath the hull bottom defining with the side fins a pair of longitudinal tunnels commonly served by said blower whereby stabilization is secured upon rolling of the hull, through the simultaneous compression of air in one tunnel and its expansion in the other tunnel due to differential water displacement on opposite sides of the hull.

4. In a power boat, the combination of a hull having longitudinal parallel side and center fins extending depthwise below the hull bottom forming parallel longitudinal tunnels beneath the hull bottom, a blower casing communicating with the forward portions of said tunnels, a blower in said casing delivering air rearwardly through said tunnels, hinged stern and bow vanes normally closing the ends of said tunnels whereby said boat is lifted upon a layer of air under pressure accumulated in said tunnels, means imparting a closing force to said stern vane, the latter being opened by air pressure in said tunnels in excess of said closing force to discharge the air flow from said tunnel against the water wake, and a gravity stabilized vane hingedly

5 mounted in said casing separating the latter into two chambers, said vane being in the plane of said center fin when the boat is on an even keel, but swinging relative to said boat when the latter rolls whereby a larger proportion of the air output from said blower is delivered to the more depressed of said tunnels for augmenting the stabilizing effect of the differential air pressure in the respective tunnels incident to the listed position of the boat.

5. In a power boat, the combination of a hull having longitudinal parallel side and center fins extending depthwise below the hull bottom forming parallel longitudinal tunnels beneath the hull bottom, a blower casing communicating with the forward portions of said tunnels, a blower in said casing delivering air rearwardly through said tunnels, hinged stern and bow vanes normally closing the ends of said tunnels whereby 15 said boat is lifted upon a layer of air under pressure accumulated in said tunnels, means imparting a closing force to said stern vane, the latter being opened by air pressure in said tunnels in excess of said closing force to discharge the air flow from said tunnel against the water wake, a gravity stabilized vane hingedly mounted in said casing separating the latter into two chambers, said vane being in the plane of said center fin when the boat is on an even keel, but swinging relative to said boat when the latter rolls whereby 20 a larger proportion of the air output from said blower is delivered to the more depressed of said tunnels for augmenting the stabilizing effect of the differential air pressure in the respective tunnels incident to the listed position of the boat, and an injector at the forward end of said tunnels through which said blower delivers air to said tunnels, effective when the boat moves forward responsive to the reactive force of air discharging from said tunnels against said water wake, to lift said bow vane above the water, entraining air from beneath said bow vane, thereby creating a forward vacuum which adds impetus to the forward movement of the 25 boat.

6. Power boat as claimed in claim 1, the lower portions of said fins each comprising a series of tilting plates arranged longitudinally, pivoted at their forward ends to the fixed portions of said fins.

50 7. In a power boat, the combination of a hull having longitudinal side and center fins extending depthwise below the hull bottom forming longitudinal tunnels beneath the hull bottom, a blower on said boat for delivering air to the forward portions of both tunnels in a rearward direction, a stern vane at the rear of said tunnels having means imparting a biasing force thereto in a direction to close said tunnels, hinged bow 55 vane normally closing the front ends of said tunnels, whereby said boat is lifted on a layer of air under pressure accumulated in said tunnels, said stern vane being opened by air pressure in said tunnels in excess of said biasing force to discharge the air flow from said tunnels against the water wake, and an injector at the forward ends of said tunnels through which said blower delivers air to said tunnels, effective when the boat moves forward responsive to the reactive force of air discharging from said tunnels against the water wake, to lift said bow vanes above the water, entraining air from beneath said bow vanes, thereby creating a forward vacuum which adds impetus to the forward movement of the 60 boat.

8. In a power boat, the combination of a hull having longitudinal side and center fins extending depthwise below the hull bottom forming longitudinal tunnels beneath the hull bottom, blower casings communicating with the respective tunnels at their forward ends, independently controlled blowers in said casings for delivering air to said respective tunnels in a rearward direction, a stern vane at the rear of said tunnels having means imparting a biasing force thereto in a direction to close said tunnels, hinged bow vanes normally closing the front ends of said tunnels whereby said boat is lifted on a layer of air under pressure accumulated in said tun-

nels, said stern vane being opened by air pressure in said tunnels in excess of said biasing force to discharge air flow from said tunnels against the water wake, and injectors at the forward ends of said tunnels through which said blowers deliver air to the respective tunnels, effective when the boat moves forward responsive to the reactive force of air against the water wake to lift said bow vanes above the water, entraining air from beneath said bow vanes thereby creating a forward vacuum which adds impetus to the forward movement of the boat.
